 Filed May 31, 1962, Ser. No. 199,173
 6 Claims. (Cl. 74—817)

This invention relates to turntables and has particular reference to turntables for supporting several sets of apparatus to be brought sequentially by rotation of the turntable into a predetermined location.

According to the present invention, a turntable includes an indexing mechanism comprising a carriage movable along a path lying tangentially with respect to a circle described about the axis of rotation of the turntable, a lever pivotally mounted on the carriage so as to swing in a horizontal plane and about a point lying on the line of tangential movement, means for coupling the turntable to, and uncoupling the turntable from, the lever and an arrangement for reciprocating the carriage along its path of movement.

Preferably, the means for reciprocating the carriage comprises a fluid operated piston and cylinder assembly, the carriage being operatively connected to the movable member of the assembly.

The turntable may be equipped with a locking device which locks the table against movement when the latter is uncoupled from the lever. Desirably, the locking device is interlocked with the means for coupling the uncoupling in such manner that, at no time, is the table uncoupled from the lever and not locked by the locking device.

Fluid-operated braking means may be fitted adjacent the piston and cylinder assembly to assist in reducing the speed of the turntable prior to the latter being brought to a standstill at the end of the stroke of the assembly.

In one embodiment of the invention, the turntable is coupled to the lever by means of a driving pin moved by a fluid operated piston and cylinder assembly mounted on the lever. That assembly includes limit valves which interlock it with another assembly for operating a locking pin forming part of the locking device. Both pins co-operate with recesses in blocks mounted on the turntable, for example, secured to the underneath surface thereof. The recesses in the blocks may be of conical form so that the pins are then self-centering and remain so despite wear.

By way of example only, an embodiment of the invention will now be described in greater detail with reference to the accompanying drawings of which:

FIG. 1 is a plan view of part of the indexing mechanism of the embodiment,

FIG. 2 is a section on the line II—II of FIG. 1 and includes part of the turntable, and,

FIG. 3 shows the pneumatic circuit of the embodiment in block schematic form.

The turntable is of annular form when seen in plan and is supported upon suitable bearings enabling it to rotate about a central vertical axis. The bearings lie between that axis and the inner circumference of the annulus so that the central opening is left clear for electrical leads, supply pipes or other apparatus which may have to be connected to apparatus on the surface of the turntable. Secured to the undersurface of the turntable and equi-spaced round the axis of rotation are six blocks apertured centrally to engage locking and driving pins in a manner described later. Thus, in FIG. 2, is shown part of the turntable 1 and two, 2, 3, of the six apertured blocks. The apertures in the blocks are of conical form.

Located beneath the turntable is a framework supporting a main pneumatically operated piston 4 and cylinder 5 assembly orientated so that the piston 4 can be extended and retracted along a line which is a tangent to a circle drawn about the axis of rotation of the turntable through the apertures in the blocks. Secured to the outer end of the piston is a carriage 6 movable along spaced guides 7, 8 and carrying parallel spaced levers 9 pivotally mounted on the carriage. The levers are fixed to the ends of a vertical pivot pin 10 rotatably mounted in a bearing sleeve 11 on the carriage. The arms of the levers are of about equal length and at one end the levers carry a tubular guide 12 and at the other a pin 13 whose ends travel in arcuate slots 14 in the framework of the carriage. The arcuate slots lie across the line of movement of the piston of the main assembly as can be seen in FIG. 1.

On each side of the cylinder 5 of the main assembly is a pneumatic brake comprising a piston-cylinder-assembly 15 whose piston carries a buffer pad 16 for engagement with a shoulder on the carriage.

As can be seen in FIG. 2, the tubular guide 12 supports, at its lower end, a pneumatically operated piston and cylinder assembly 17 to whose piston 18 is secured a driving pin 19.

Also located beneath the turntable is a locking device comprising a locking pin 20 movable vertically along a suitable guide 21 by a pneumatic piston-cylinder assembly 22. The locking device is positioned such that the locking pin can be projected upwardly at an appropriate moment to engage the aperture in one of the blocks 3 mentioned above.

The length of stroke of the piston 4 is selected in accordance with the number of blocks and in the embodiment each of the six blocks is engaged in turn by the driving pin 19 at one end of the stroke and disengaged at the other end. Thus, no pivotal movement of the lever 9 is necessary between the disengagement of one block and the engagement of a succeeding block, so long as the machine is started with the engaged block in a position such that the chords connecting the arc through which said engaged block will be driven is parallel to the path of travel of the piston.

The various piston and cylinder assemblies are provided with control valves which are operated in a manner now to be described with reference to FIG. 3 which shows the pneumatic circuit in block schematic form, all valves being shown in their normal, unoperated positions.

Associated with the piston 4 are limit switches actuating changeover valves 23 and 24 arranged as shown at opposite ends of the stroke of the piston. Valve 24 may also be operated by compressed air. The flow of compressed air to the cylinder 5 is controlled by a changeover valve 25 operated by pneumatic pressure supplied via either start valve 26 or a control valve 27 located at one end of the stroke of the piston actuating the driving pin 19. At the other end of the stroke of that piston is another control valve 28. Associated with the piston actuating the locking pin 20 is a control valve 29, the supply of compressed air to cylinder assembly 22 of the piston being controlled by a pneumatic pressure operated valve 30. A similar pressure operated valve 31 controls the supply of compressed air to cylinder assembly 17.

In the flow lines from valve 25 to the cylinder 5 are pressure operated valves 32 and 33 operation of which is under the control of a manually operated emergency stop control 34 and a reset control 35. Operation of control 34 closes valves 32 and 33 regardless of the position of the piston 4 thereby bringing the latter to a standstill. Movement is resumed by operation of the reset control 35. FIG. 3 also shows the pneumatic brakes 15 to the pneu-

3

matic circuits of which is coupled an adjustable pressure regulator valve 36 which determines the resistance offered by the brakes. The effective resistance is indicated by a pressure indicator 37. Also included in the pneumatic circuit are flow regulators indicated diagrammatically at 38.

Initially, the driving pin 19 is extended into the aperture in one of the blocks on the undersurface of the turntable whilst the locking pin 20 is disengaged and in this position piston 4 of cylinder 5 is in its extended position. Actuation of the main control valve 26 admits compressed air to the cylinder 5, the piston 4 of which starts to retract thereby moving the carriage 6 along the guides 7, 8 and the turntable rotates through 60°. The piston 4 is brought to a standstill at the end of its stroke by pneumatic brakes 15 and limit valve 23 is operated. In that position shown in FIG. 3, the locking pin 20 is directly below one of the apertured blocks. The limit valve 23 also operates valve 30 which permits compressed air to flow to the piston-cylinder assembly 22 of the locking pin 20 and the latter is advanced into the aperture block 3 above it. Completion of that movement operates limit valve 29 which actuates valve 31 of the piston-cylinder assembly 17 of the driving pin which is then withdrawn by the application of compressed air to cylinder 17. The turntable is now locked so that when the cylinder 5 is energised by valve 27 operating valve 25 its piston 4 is extended.

At the other end of the stroke of piston 4, valve 24 is operated and the sequence is reversed. Driving pin 19 is moved into engagement with an apertured block 2 after which locking pin 20 is withdrawn and the full sequence may be repeated by operation of control valve 26.

During movement of the turntable the piston of the main assembly moves linearly along a path tangential to a circle which is described about the axis of rotation of the turntable and the pivot point 10 of the levers 9 follows the same path. The driving pin 19 however follows an arcuate path beginning at one end of said tangential path and ending at the other end of said tangential path so that the levers pivot during movement of the carriage and are guided during that movement by the guide pin 13 which travels back and forth along the arcuate slots 14.

Just before the end of the stroke of the piston of the main assembly, the carriage shoulders engage the buffer blocks 16 on the pneumatic brakes 15 thereby slowing the turntable preparatory to the latter being brought to a standstill at the end of a stroke of a piston. The instant of engagement of buffer blocks and shoulders occurs when the lever is in line with the piston of the main assembly.

The sequence described above can be made to repeat either automatically or under a manually operable control.

It will be appreciated that at no time is the turntable free of both pins and this ensures greater accuracy of indexing and control of movement. The linear movement of the piston of the main assembly as well as of the pivotal axis of the lever is translated by the latter into an arcuate movement of the driving pin.

The main piston-cylinder assembly may be hydraulically operated as may the other assemblies or alternatively some other form of drive for the carriage may be used. Pneumatic operation is particularly suitable in the case of very heavy turntables which also require pneumatic brakes described above although the latter may not be needed for turntables of lighter weight.

I claim:

1. A turntable assembly comprising, in combination, a turntable, a linear actuator including a movable member and fixed guide means restricting said movable member to rectilinear motion along a path tangent to a circle concentric with the turntable, a plurality of sockets mounted on the turntable adjacent the periphery thereof in a ring concentric with said turntable and spaced from each other

5 by a chord equal to the length of stroke of the movable member, a lever pivotally mounted upon the movable member to turn about an axis parallel to the axis of the turntable, and a driving pin mounted on the lever in a position which is in alignment with one of said sockets at one limit of the stroke of the movable member, said pin being mounted for sliding movement relative to said lever which brings it into driving engagement with said aligned socket so as to propel said aligned socket during the subsequent stroke of the movable member, along an arc of said ring whose chord is equal in length and parallel to the stroke of said movable member.

2. A turntable assembly comprising, in combination, a turntable, a linear actuator including a movable member and fixed guide means restricting said movable member to rectilinear motion along a path tangent to a circle concentric with the turntable, a plurality of sockets mounted on the turntable adjacent the periphery thereof in a ring concentric with said turntable and spaced from each other by a chord equal to the length of stroke of the movable member, a lever pivotally mounted upon the actuator to turn about an axis parallel to the axis of the turntable, a driving pin mounted on the lever in a position which is in alignment with one of said sockets at one limit of the stroke of the actuator, said pin being mounted for sliding movement relative to said lever which brings it into driving engagement with said aligned socket so as to propel said aligned socket during the subsequent stroke of the actuator, along an arc of said ring whose chord is equal in length to the stroke of said actuator, and a slideable pin mounted on a stationary portion of said assembly for engagement with the sockets whereby the turntable may be held against rotation.

3. A turntable assembly comprising, in combination, a turntable, a linear actuator including a movable member and fixed guide means restricting said movable member to rectilinear motion along a path tangent to a circle concentric with the turntable, a plurality of sockets mounted on the turntable adjacent the periphery thereof in a ring concentric with said turntable and spaced from each other by a chord equal to the length of stroke of the movable member, a lever pivotally mounted upon the movable member to turn about an axis parallel to the axis of the turntable, a driving pin mounted on the lever in a position which is in alignment with one of said sockets at one limit of the stroke of the movable member, said pin being mounted for sliding movement relative to said lever which brings it into driving engagement with said aligned socket so as to propel said aligned socket during the subsequent stroke of the movable member, along an arc of said ring whose chord is equal in length and parallel to the stroke of said movable member, and a brake whereby the turntable is brought to rest after rotation by the movable member.

4. A turntable assembly comprising, in combination, a turntable, a linear actuator including a movable member and fixed guide means restricting said movable member to rectilinear motion along a path tangent to a circle concentric with the turntable, a plurality of sockets mounted on the turntable adjacent the periphery thereof in a ring concentric with said turntable and spaced from each other by a chord equal to the length of stroke of the movable member, a lever pivotally mounted upon the movable member to turn about an axis parallel to the axis of the turntable, a driving pin mounted on the lever in a position which is in alignment with one of said sockets at one limit of the stroke of the movable member, said pin being mounted for sliding movement relative to said lever which brings it into driving engagement with said aligned socket so as to propel said aligned socket during the subsequent stroke of the movable member, along an arc of said ring whose chord is equal in length and parallel to the stroke of said movable member, a slideable pin mounted on a stationary portion of the assembly for engagement with the sockets whereby the turntable may be held

against rotation, and a brake whereby the turntable is brought to rest after rotation by the movable member.

5. A turntable assembly comprising, in combination, a turntable, a linear actuator including a movable member and fixed guide means restricting said movable member to rectilinear motion along a path tangent to a circle concentric with the turntable, a plurality of sockets mounted on the turntable adjacent the periphery thereof in a ring concentric with said turntable and spaced from each other by a chord equal to the length of stroke of the movable member, a lever pivotally mounted upon the movable member to turn about an axis parallel to the axis of the turntable, a driving pin mounted on the lever in a position which is in alignment with one of said sockets at one limit of the stroke of the movable member, said pin being mounted for sliding movement relative to said lever which brings it into driving engagement with said aligned socket so as to propel said aligned socket during the subsequent stroke of the movable member, along an arc of said ring whose chord is equal in length and parallel to the stroke of said movable member, a 10 slideable pin mounted on a stationary portion of said assembly for engagement with the sockets whereby the turntable may be held against rotation, and a hydraulic control system for actuating said pins which ensures that at 15 least one socket is always engaged by one of the two pins.

6. A turntable assembly comprising, in combination, a turntable, a linear actuator including a movable member and fixed guide means restricting said movable member 20 to rectilinear motion along a path tangent to a circle

concentric with the turntable, a plurality of sockets mounted on the turntable adjacent the periphery thereof in a ring concentric with said turntable and spaced from each other by a chord equal to the length of stroke of the movable member, a lever pivotally mounted upon the actuator about an axis parallel to the axis of the turntable, a driving pin mounted on the lever in a position which is in alignment with one of said sockets at one limit of the stroke of the movable member, said pin being mounted for sliding movement relative to said lever which brings it into driving engagement with said aligned socket so as to propel said aligned socket during the subsequent stroke of the actuator, along an arc of said ring whose chord is equal in length to the stroke of said movable member, a slideable pin mounted on a stationary portion of said assembly for engagement with the sockets whereby the turntable may be held against rotation, a brake whereby the turntable is brought to rest after rotation by the movable member, and a hydraulic control system for actuating said slideable pins which ensures that at least one socket is always engaged by one of the two pins.
